FLEXIBLE ESOPHAGOSCOPE

Ludwig Streifeneder, Chicago, Ill.

Application April 11, 1955, Serial No. 35,454

Term of patent 14 years

(Cl. D83—1)

Fig. 1 is a reduced top plan view of a flexible esophagoscope, embodying my new design.

Fig. 2 is a full size bottom view of Fig. 1, partly broken away.

Fig. 3 is an enlarged end view of Fig. 1.

Fig. 4 is a section on line 4—4, Fig. 1, to illustrate the external contour of the new design of a flexible esophagoscope.

I claim:

The ornamental design for a flexible esophagoscope, as shown.
